Specification for Design.

Patented Aug. 1, 1922.

Application filed November 14, 1921. Serial No. 515,140. Term of patent 14 years.

To all whom it may concern:

Be it known that I, FREDERICK A. BOLLINGER, a citizen of the United States, residing at Akron, in the county of Summit and State of Ohio, have invented a new, original, and ornamental Design for Tire Treads, of which the following is a specification, reference being made to the accom-

panying drawings, forming a part thereof.

In the drawings, Fig. 1 is a plan view of the tire tread and Fig. 2 is a transverse section through the tread.

I claim:

The ornamental design for a tire tread as shown.

FREDERICK A. BOLLINGER.
